UNITED STATES PATENT OFFICE.

NICHOLAS R. MAUS, OF CHICAGO, ILLINOIS.

AUTOMATIC RELEASE-VALVE.

SPECIFICATION forming part of Letters Patent No. 770,646, dated September 20, 1904.

Application filed March 15, 1904. Serial No. 198,318. (No model.)

To all whom it may concern:

Be it known that I, NICHOLAS R. MAUS, a citizen of the United States, residing at Chicago, in the county of Cook and State of Illinois, 55 have invented new and useful Improvements in Automatic Release-Valves, of which the following is a specification.

This invention relates to an automatically-operating release-valve for use in connection 10 with engine-cylinders; and the primary object of the same is to provide a device of this class having means which will prevent suction through the valve to the cylinder when steam is shut off from the cylinder and engine is 15 still in motion and also to have the operative elements of the valves so arranged that they will be double-acting, and thereby require the use of a single-valve structure only with each cylinder to arrive at the result sought.

20 A further object of the invention is to provide a valve of the class set forth having the parts arranged for ready assemblage and to facilitate the application thereto of connections.

25 With these and other objects and advantages in view the invention consists of a casing having two lower inlet extensions bored or otherwise formed with valve-receiving seats in which connected valves having simultaneous 30 operation are arranged, and coöperating with the latter is a check-valve having a gravitating movement and controlling the outlet of the steam received in the improved valve into an atmospheric outlet.

35 The invention further consists in the details of construction and arrangement which will be more fully hereinafter set forth.

In the drawings, Figure 1 is a longitudinal vertical section of a valve embodying the 40 features of the invention. Fig. 2 is an end elevation of a portion of the valve. Fig. 3 is a bottom plan view of a check-valve disk plate or limiting means used in connection with the improved device. Fig. 4 is a top 45 plan view of the valve, showing the disk plate removed. Fig. 5 is a bottom plan view of the check-valve.

Similar numerals of reference are employed to indicate corresponding parts in the several 50 views.

The numeral 1 designates a valve-casing having lower extensions 2 projecting outwardly therefrom and arranged in diametrical alinement, the extremities of said extensions being externally screw-threaded, as at 3, and the terminals having circumferential cavities for facilitating the application of pipe connections to said extensions and the formation of ball-joints. The extensions are longitudinally bored to form seats 5, which communicate at their extremities by means of reduced 60 passages 6 with a central chamber 7, curved shoulders 8 being provided at the intersection of the inner terminals of the seats and the throats. Rising from the casing at a point 65 in central relation to the extensions 2 is a vertical extension 9, having a bore 10 communicating with the chamber 7 and formed with an upper enlargement to provide a seat 11, terminating at a lower curved shoulder 70 12. The upper end of the vertical extension 9 is externally screw-threaded, as at 13, and extending longitudinally through the inner portions of the ends of the extensions 2 and 9 are segmental steam passages or ports 75 14. A disk plate or limiting device 15 is arranged on the upper end of the vertical extension 9 and is of less diameter than said end. This disk plate or limiting means has an upper circumferential cavity 16 to facilitate the formation of a ball-joint in relation 80 to the pipe connection adapted to be secured to the upper end of the extension 9, and said disk plate or limiting means is also formed with segmental escape openings or outlets 17 85 and a central stop-web 18, the opening 17 communicating with the enlargement 11 of the port 10. The disk plate or limiting means 15 when applied to the upper end of the extension 9 closes the upper open terminals of 90 the segmental passages or ports 14; but the latter are long enough to establish communication between different portions of the enlargement 11 of the bore when a valve, which will be presently described, coöperating therewith is in certain positions.

Slidably mounted in the seats 5 are valves 19, having inwardly-projecting stems 20, and extending centrally through both valves and stems thereof are bores 21 to receive a coup- 100

ling-bolt 22, having a head 23 at one end and securing and jam nuts 24 and 25 on the opposite end. When the valves 19 and their stems 20 are properly assembled and connected by the bolt 22, the inner ends of the stems closely abut against each other, and the proportions and distance between the valves is so determined primarily that when one valve is in closed position the other will be open, and 5 as both valves are firmly attached they will have a simultaneous operation equally in opposite directions. The stems 20 of the valves are materially less in diameter than the throat 6, and to facilitate the operation of the valves, 10 as well as to lighten the same, they are cored out or recessed from their outer faces inwardly, as at 26.

A check-valve 27 is arranged in the enlargement or seat 11, forming part of the bore 10, 20 and has a depending winged stem 28 movable in said bore and comprising intersecting wings to form angular passages 29, as clearly shown by Fig. 5. The upper face of the valve 27 is also circumferentially recessed, as at 30, 25 to lighten the same, and extending upwardly from the center of the said valve is a stop projection 31, which is adapted to contact with the lower face of the web 18 of the plate or limiting means 15. By the use of this 30 limiting-plate the upward movement of the valve is restricted, said valve being permitted to rise high enough to clear the lower extremities of the passages or ports 14 when the said check-valve is subjected to pressure. 35 When the valve is free of operating-pressure, it will gravitate and close against the shoulder 12. The pipe connection, which is adapted to be applied to the upper end of the extension 9, will communicate with the atmosphere or a stack, and the pipes, which are attached to the extensions 2, will communicate with opposite extremities of an engine-cylinder and also with means for feeding steam to the opposite ends of the valve from a boiler. 40 45 to properly dispose the dual valve to permit the exhaust-steam from opposite ends of a cylinder to which it may be connected to pass therethrough and escape through the actuation of the check-valve into the atmosphere. 50 When an engine embodying a cylinder to which the improved valve is attached is in operation and steam passes into one end of the cylinder, the valve at the right, for instance, will be simultaneously affected by such 55 steam-pressure from the boiler and assume a closed position and simultaneously open the valve at the left ready to receive the steam that remains in the cylinder after the main engine-valve exhausts, this exhaust passing 60 into the extension. The exhaust passing into the extension through and around the valve at the left will enter the chamber 7 through the adjacent throat 6 and raise the check-valve and pass out through the ports 14 and 65 plate or limiting means 15 into a stack or the

atmosphere in accordance with the attachment of the pipe connection coöperating with the upper end of the vertical extension 9. The opposite or right-hand valve of the dual-valve arrangement will be open and the left-hand valve closed when steam is admitted into the opposite end of the cylinder, and this operation becomes successive and regular until the steam is shut off from the cylinder. 70

The passage of the steam through the improved valve causes a draft to be set up in the stack if the valve is attached to the latter, and by means of such draft the fire in the furnace will be benefited and steam more quickly and plentifully generated. Furthermore, the 80 operation of the improved valve overcomes any tendency to the institution of back pressure in the cylinder after the steam has been used and is exhausted, and during the operation of exhausting the steam from the cylinder by means of the improved valve one valve will remain open the full length of the stroke of a piston in the cylinder or until steam is admitted to the end of the cylinder opposite that primarily receiving the steam. Furthermore, the gravitating check-valve obstructs any tendency to suction or back pressure by immediately returning to its seat or to closed position when the exhaust is completed. This is a material advantage and is beneficial to 90 the mechanism coöperating with the engine-cylinder. 95

It is preferred to construct the several parts of the valve with cast-brass and to have the coupling-bolt 22 formed of soft steel. It will 100 be understood, however, that other metals may be employed. In addition to the advantages of creating a draft in a stack by the use of a valve the latter will be also beneficial in saving cylinder-oil and fuel. It will also be 105 understood that changes in the proportions, dimensions, and minor details may be resorted to without departing from the spirit of the invention.

Having thus described the invention, what 110 is claimed as new is—

1. In a device of the class set forth, the combination of a casing, a dual valve automatically operating in the lower part of the casing and having a single connecting means, and a check-valve movable in planes at right angles to and at a distance from the dual valve. 115
2. In a device of the class set forth, the combination of a casing having diametrically-opposed inlets, a dual valve operating in conjunction with said inlets and having a single connecting means, and a check-valve arranged at an angle to the dual valve, both valves having an automatic operation and the stem of the check-valve being always at a distance 120 from the connecting means for the dual valve. 125
3. In a device of the class set forth, the combination of a valve-casing having diametrically-opposed inlets formed with valve-seats, and an angular extension also formed with a 130

seat, all the seats having ports therearound communicating therewith, two valves operating in connection with the first-mentioned seats and having a single connecting means, 5 and a check-valve mounted in the extension, the latter communicating with the inlets and having its stem at all times at a distance from the connecting means of the said two valves.

4. In a device of the class set forth, the combination of a casing having lower diametrically-opposed extensions forming inlets and provided with seats, a vertical extension communicating with the inlets and also having a seat at its outlet end, the extensions adjacent 15 to all the seats being provided with ports arranged therearound, valves slidably mounted in the seats of the inlet extensions and connected for simultaneous operation, and a check-valve automatically slidable in the vertical extension and having a winged stem always located at a distance from the connecting means for the valves mounted in the inlet extensions.

5. In a device of the class set forth, a valve-casing having inlet-terminals provided with seats and an outlet-terminal also having a seat, valves slidably mounted in the seats of the inlet-terminals and connected for simultaneous operation, one of the latter valves being 25 open when the other is closed, and an automatically-operating check-valve arranged in the outlet-terminal and having a winged stem always located at a distance from the connecting means for the valves mounted in the inlet- 30 terminals.

6. In a device of the class set forth, the combination of a casing having inlet-terminals, an outlet-terminal in communication with the first-named terminals, all the terminals having 35 seats and ports around the said seats, valves

in the seats of the inlet-terminals having inwardly-extending stems, a bolt extending through the valves in the inlet-terminals to connect the same for simultaneous operation, and an automatically-operating check-valve in 45 the outlet-terminal having a winged stem always located at a distance from the inwardly-extending stems of the valves in the inlet-terminals.

7. In a device of the class set forth, the combination of a casing having lower inlet-terminals provided with seats and ports, an outlet-terminal having a seat and ports, the outlet-terminal communicating with the inlet-terminals, connected sliding valves arranged in the 55 seats of the inlet-terminals, a slideable check-valve in the seat of the outlet-terminal, and means for limiting the movement of the said check-valve.

8. In a device of the class set forth, the combination of a casing having lower extensions provided with seats and ports, and throats leading to a central chamber, an angular and vertical extension between said lower extensions having a bore communicating with the 65 said chamber, and an upper seat and ports, a dual slide-valve mounted in the seats of the lower extensions, a check-valve slidably mounted in the seat of the vertical extension and having a winged stem, and a limiting- 70 plate on the upper end of the vertical extension provided with openings therethrough, and a stop means to engage a part of the valve in the vertical extension.

In testimony whereof I affix my signature in 75 presence of two witnesses.

NICHOLAS R. MAUS.
